(57) **CLAIM**

The ornamental design of a suspended luminaire, as shown and described.

DESCRIPTION

FIG. 1 is a perspective view of a first embodiment of the luminaire showing the new design;

FIG. 2 is an elevational view thereof;

FIG. 3 is a bottom view thereof;

FIG. 4 is a top plan view thereof;

FIG. 5 is a perspective view of a second embodiment of a luminaire showing the new design;

FIG. 6 is an elevational view thereof;

FIG. 7 is a bottom view thereof; and,

FIG. 8 is a top plan view thereof.

The broken lines shown on the drawings are for illustrative purposes only and form no part of the claimed design.
